UNITED STATES PATENT OFFICE

FOORD von BICHOWSKY, OF GLENDALE, CALIFORNIA, ASSIGNOR TO TITANIA CORPORATION, OF LOS ANGELES, CALIFORNIA, A CORPORATION OF CALIFORNIA.

METHOD FOR PRODUCING TITANIUM COMPOUNDS AND COMPOUNDS OF NITROGEN

No Drawing.

Application filed October 30, 1929. Serial No. 403,660.

The present invention relates to a method for producing titanium compounds and especially to the production of oxygen containing titanium compounds together with the recovery of the nitrogen of the titanium compounds in the form of combined nitrogen.

I have described, in my United States Letters Patent Number 1,742,674 dated January 7, 1930, the preparation of titanium oxide from titanium nitride by acting upon the latter with nitric acid. In another pending application for patent Serial No. 320,762 filed November 20th, 1928, I describe the acting upon titanium nitride with nitric acid in the presence of sulphuric acid and show that from this reaction there results titanium acid sulphates. In the practicing of these discoveries, however, only a fraction of the nitride nitrogen of the titanium nitride is recoverable as ammonia or in other combined form.

I have now found that by acting upon titanium nitrogen compounds and especially the reactive nitrogen compounds prepared by the methods of my United States Letters Patent Number 1,408,661, dated March 7, 1922, with halogens or halogen compounds under oxidizing conditions and in the presence of water and an acid that one obtains oxygen containing compounds of titanium together with ammonium salts. The ammonium compounds, which are often obtained in very good yield, are formed from the nitride nitrogen of the titanium nitride or cyanonitride.

As an example: One heats together titanium nitride and a 60 per cent solution of perchloric acid. Dense fumes are soon given off. When the reaction is over the resulting white pasty mass, upon washing with water, gives as a residue titanium dioxide while the wash water contains ammonium compounds. The recovery of the nitrogen of the nitride in the form of ammonium perchlorate, ammonium chlorate, etc., is practically quantitative.

As a further example of my discovery: If one warms together titanium nitride and a mixture of diluted sulphuric acid (sp. g. 1.40) and strong perchloric acid (sp. g. 1.54) in excess of the theory one obtains a solution of

acid titanium sulphate and ammonium sulphate. The yields are nearly quantitative. If desired one may further dilute such a solution, filter, pass in sulphur dioxide, and warm for some hours at about 70° C., whereupon one obtains pure titanium oxide. The solution after filtering off the TiO_2 may be worked up for the recovery of the ammonium compounds present.

If one uses, instead of perchloric acid, a solution of sodium or calcium hypochlorite in the presence of hydrochloric acid or even solutions of chlorine in water, either with or without phosphoric acid or phosphates, one can obtain, from titanium nitride, ammonium salts and titanium dioxide.

One may also use the halates, perhalates or hypohalites of other alkali or alkaline earth metals. It is further evident that these oxygenated halogen salts or their acids may be produced electrolytically in the presence of titanium nitride, water and a free acid.

As an example: If an aqueous solution of sodium chloride, in which is suspended titanium nitride and containing a little hydrochloric acid, be electrolyzed, in a suitable cell, one obtains titanium oxide and ammonium salts.

It is to be understood that I do not confine my invention to the examples as given for they may be modified by one skilled in the art without departing from the scope of this invention.

What I claim as new and desire to secure by Letters Patent is:

1. Method for the production of titanium compounds containing oxygen by acting upon titanium nitrogen compounds with halogen compounds having an oxidizing action and in the presence of water and a free acid and recovering the nitrogen of the titanium nitrogen compound in a combined form.

2. Method for the production of titanium compounds containing oxygen and especially titanium acid sulphates by acting upon titanium nitrogen compounds with oxidizing halogen compounds in the presence of water and sulphuric acid and recovering the nitrogen of the titanium nitrogen compound in a combined form.

3. Method for the production of titanium compounds containing oxygen and especially titanium oxide by acting upon titanium nitride with oxygenated halogen compounds in the presence of water and phosphoric acid and recovering the nitrogen of the titanium nitrogen compound as an ammonium phosphate. 70
4. Method for the production of titanium compounds containing oxygen and especially titanium dioxide by acting upon titanium nitrogen compounds with a hypochlorite of an alkaline metal in the presence of water and a halogen acid and recovering the nitrogen of the titanium nitrogen compound as an ammonium compound. 75
5. Method for the production of titanium compounds containing oxygen and especially titanium dioxide by acting upon titanium nitrogen compounds with a chlorate of an alkaline metal in the presence of water and a halogen acid and recovering the nitrogen of the titanium nitrogen compound as an ammonium compound. 80
6. Method for the production of titanium compounds containing oxygen and especially titanium dioxide by acting upon titanium nitrogen compounds with a perchlorate of an alkaline metal in the presence of water and a halogen acid and recovering the nitrogen of the titanium nitrogen compound as an ammonium compound. 85
7. Method for the production of titanium compounds containing oxygen and especially titanium acid sulphate by acting upon titanium nitrogen compounds with hypochlorous acid in the presence of water and sulphuric acid and recovering the nitrogen of the titanium nitrogen compound as ammonium sulphate. 90
8. Method for the production of titanium compounds containing oxygen and especially titanium acid sulphate by acting upon titanium nitrogen compounds with chloric acid in the presence of water and sulphuric acid and recovering the nitrogen of the titanium nitrogen compound as ammonium sulphate. 95
9. Method for the production of titanium compounds containing oxygen and especially titanium acid sulphate by acting upon titanium nitrogen compounds with perchloric acid in the presence of water and sulphuric acid and recovering the nitrogen of the titanium nitrogen compound as ammonium sulphate. 100
10. Method for the production of titanium compounds containing oxygen and especially sodium titanium acid sulphate by acting upon titanium nitride and sulphuric acid with an aqueous solution of sodium hypochlorite and recovering the nitrogen of the titanium nitride in the form of ammonium sulphate. 105
11. Method for the production of titanium compounds containing oxygen and especially titanium acid sulphate by acting upon titanium nitride with hypochlorous acid in the presence of sulphuric acid and water and recovering the nitrogen of the titanium nitride as ammonium sulphate. 110
12. Method for the production of titanium oxide by acting upon titanium nitride with hypochlorous acid in the presence of water and sodium phosphate. 115
